(22) Filed: **Dec. 9, 2011**

CLAIM

The ornamental design for a motor vehicle, toy and/or replica, as shown and described.

(30) **Foreign Application Priority Data**

DESCRIPTION

Jun. 10, 2011 (DE) 40 2011 006 018

FIG. 1 is a front perspective view of a motor vehicle, toy and/or replica;

(51) **LOC (10) Cl.** **12-08**

FIG. 2 is a rear perspective view of the motor vehicle, toy and/or replica;

(52) **U.S. Cl.**

FIG. 3 is a front elevation view of the motor vehicle, toy and/or replica;

USPC **D12/92**

FIG. 4 is a rear elevation view of the motor vehicle, toy and/or replica;

(58) **Field of Classification Search**

FIG. 5 is an elevation view from the left side of the motor vehicle, toy and/or replica, the right side being substantially a mirror image thereof;

USPC D12/86, 90-92; D21/424, 433, 434;
296/181.1, 181.5

FIG. 6 is a top plan view of the motor vehicle, toy, and/or replica with the top down;

See application file for complete search history.

FIG. 7 is a front perspective view of the motor vehicle, toy and/or replica of FIG. 6;

(56) **References Cited**

FIG. 8 is a rear perspective view of the motor vehicle, toy and/or replica of FIG. 6;

U.S. PATENT DOCUMENTS

FIG. 9 is a front perspective view of the motor vehicle, toy and/or replica of FIG. 6;
